UNITED STATES PATENT OFFICE.

JAMES STEPHENS, OF WASHINGTON, INDIANA, ASSIGNOR OF ONE-HALF TO
J. F. LINDLEY, JR., OF SAME PLACE.

DRAWER.

SPECIFICATION forming part of Letters Patent No. 280,412, dated July 3, 1883.

Application filed March 29, 1883. (No model.)

To all whom it may concern:

Be it known that I, JAMES STEPHENS, a citizen of the United States, residing at Washington, in the county of Daviess and State of Indiana, have invented a new and useful 5 Drawer, of which the following is a specification, reference being had to the accompanying drawings.

This invention relates to drawers especially 10 adapted for depositing money, and it has for its object to provide safe, convenient, and efficient means for "making change," as it is called, whereby the operator can perform this action with ease and rapidity.

15 To this end my invention consists in certain improvements in the construction and combination of devices, as will be hereinafter fully set forth and claimed.

In the accompanying drawings, Figure 1 20 represents a perspective view of my money-drawer, one of the crank-levers being shown as turned down in the act of making change. Fig. 2 represents a perspective view from the back, the casing being partly removed, showing the interior arrangement, and the parts 25 being shown in the locked position. Fig. 3 represents a vertical longitudinal section of the same. Fig. 4 represents a transverse vertical section through the coin-receiving chambers. Fig. 5 represents a detail view of the 30 device for locking the levers and sounding the alarm.

Similar letters refer to corresponding parts in all the figures.

35 Referring to the drawings, A designates a suitable casing provided at the front end with a box, B, which is divided into any number of chambers or compartments, *a*, of varying size. Said chambers are provided with openings *a'*, 40 extending from the bottom of said chamber through the box B to the front thereof, and said openings are of such a width as to permit the passage of only one coin at a time. At the top of the box a series of hoppers, *b*, formed 45 in a continuous cap-piece, are secured thereto, so as to register with each chamber or compartment. The exit-openings of said hoppers are also of varying size, and by this means coins of larger diameter than any opening will 50 not be permitted to pass through the same. These openings and the chambers are made of

such varying sizes as to permit the insertion of the silver dollar, half-dollar, quarter-dollar, dime, nickel, three-cent piece, and pennies, and the front of the box or chambers is made 55 of glass, metal, or wood, as found desirable. The hoppers *b* have inscribed thereon the names of the denomination of coin intended to be placed in each, and the front of the box, near the openings *a'*, is inscribed with similar 60 names, so as to indicate what value of coin should come out of each opening.

C designates a series of spools or reels, which revolve independently of each other on a rod, *C'*, journaled in plates *C*, secured to the back 65 of the box B. Rods or equivalent devices *c*, secured to the back of the box, separate the spools or reels from each other and permit a slight lateral movement only of the said spools on the rod. A series of crank-levers, *D*, having handles *D'*, extend through passages *d*, formed in the partitions that separate the coin-compartments from one another. Stops *d'* *d''* are secured to the back of the box B, and are arranged to limit the upward and downward movement of the end *D* of said crank-levers. Straps *d''* are attached to said ends, then pass under spools C to the levers E, and are connected to the latter. The said levers E are journaled on a rod, F, at the bottom of the 80 casing, so as to allow the front ends of the levers to move freely forward in slots *e*, formed in the part A' of the casing A. Springs G are attached to the levers E, and to the casing, and are so arranged as to give force to the 85 backward movement of the levers. Pieces *f* are secured to the bottom of the casing, one on each side of the levers E, and prevent lateral displacement of the lower ends of the same. At the upper ends of the said levers E are attached a series of rods, H, which are provided 90 with shoes I, of a width sufficient to enter slots *i* in the box B. Said slots communicate with the coin-receiving compartments, and are on a level with the bottom of the said compartments, and with the openings *a'* of the same. By this arrangement a coin resting on the bottom of any one of the compartments will be 95 expelled through the opening *a'* by the forward movement of the shoes I, produced by the 100 means as stated.

Plates J J' are attached to the part A' of

casing A, and a rod, K, is journaled in said plates, and provided with a suitable handle, K', and a fixed collar, k, the purpose of the latter being to prevent the lateral movement 5 of the said rod. The plate J has a U-shaped opening, j, so that the rod can readily be taken out of its journals. A series of arms, L, are secured on said rod, and when the handle is pushed down the said arms engage with the 10 pointed upper ends of the levers E, and while in this position the levers cannot operate the shoes.

About the middle of the rod K an arm, M, is secured. Said arm has one of its upper corners bent downward nearly at right angles to the main body of the said arm M, and when the said rod K is moved forward out of the locked position the said bent corner strikes against the depending leg of rod N, which extends from the back of the box B. When the leg is struck it is moved laterally by riding against the edges of the upper ends of the arm M, and by this movement the rod N is vibrated and strikes against a bell, O, attached to the 25 under side of the top of the casing, causing the said bell to ring. Several of these bells, with ringing devices therefor, can be added to the drawer, as may be found desirable.

The drawer P in the bottom of the casing is 30 intended for the reception of currency, bills, papers, &c. Recesses p are cut in the back part of said drawer, and are adapted to permit the free forward movement of the levers E.

The operation of my money-drawer can be 35 readily understood from the foregoing description, taken in connection with the annexed drawings. Coins are deposited in the openings of the hoppers, according to the value marked on the hoppers, and from thence pass 40 to the coin-receiving chambers. When, in making change, the operator requires a certain coin, he presses on the handle of the crank-lever D, turning the same to the position shown in Fig. 1. By this movement the 45 end D² of said lever is brought upward, abutting against the stop d', and carrying with it the strap d', which moves forward the lever E in the slots e of the casing. By the forward movement of the lever the rod H and shoe I are 50 pushed forward, the said shoe sliding through the slot in the box and pushing one coin only through the openings in the front of the box. This operation can be repeated until the desired change is obtained.

55 When it is found desirable to lock the crank-levers to keep them from being operated, the operator merely turns the handle of the rod K downward, bringing the arms L under the front ends of the levers E. While in this position the crank-levers D cannot be depressed, and thus no money can be withdrawn from the chambers. To unlock the same the rod K is turned back, and the bell is rung by the end 60 of the arm M striking against the leg of rod N, causing the latter to vibrate against the bell. Thus the downward movement of the rod will

readily lock the levers and prevent the withdrawal of any money, and the same cannot be unlocked without giving the alarm.

My device is simple and efficient, and can 70 be manufactured at a very slight expense.

The coin-receiving chambers are made either round or square, and the front of the chambers are made of either wood, glass, or metal, as preferred.

75

What I claim is—

1. In a money-drawer, the combination of the coin-receiving compartments, each provided with an opening, a², devices for expelling the coin through said openings, a rod, K, 80 having arms L, arranged to lock the said devices, and means for unlocking the rod from the exterior of the money-drawer, substantially as set forth.

2. In a money-drawer, the combination of 85 the coin-receiving compartments of varying size, each provided with an opening, a², in the front portion of the same, devices for expelling the coin through said openings, and mechanism for locking the said devices, said mechanism being provided with an alarm adapted to give notice of the unlocking of said devices, as set forth.

90

3. In a money-drawer, the combination of the coin-receiving compartments of varying 95 sizes, and provided with openings a², with crank-levers passing through the partitions of said compartments, spools or sleeves attached to the back of said compartments, levers E, moving at their upper ends in slots of the casing, straps for connecting the crank-levers with the levers E, and devices attached to said levers E for expelling the coin through the openings a², substantially as set forth.

100

4. In a money-drawer, the combination of 105 the coin-receiving compartments provided with openings a², levers E, moving at their upper ends in slots of the casing, and connecting with devices for expelling the coin through the openings a², and crank-levers connecting 110 with said levers E, as herein set forth.

5. In a money-drawer, the combination of the coin-receiving compartments formed in a box, B, of the casing, openings a², spools or reels journaled in a rod attached to the back 115 of said box, crank-levers passing through said box, levers E, journaled on a rod in the bottom of the casing and moving freely in the slots e, shoes attached to said levers E and moving in the slots i, and devices connecting 120 the crank-levers with the levers E, as set forth.

6. In a money-drawer, the combination of the coin-receiving compartments formed in a box, B, of the casing, openings a², a rod journaled to the back of said box, carrying spools or reels C, crank-levers passing through said box, levers E, journaled on a rod at the bottom of the casing, and having springs G, said levers E moving freely at their upper ends in 125 slots e of casing A', rods connected to said levers, and carrying shoes I, straps passing 130

under the spools and connecting the crank-levers with the levers E, and devices for locking the levers E, as set forth.

7. In a money-drawer, the combination of 5 the series of coin-receiving compartments formed in a box, B, of the casing, openings a^2 , a rod journaled to the back of said box, and carrying spools or reels C, crank-levers passing through said box, levers E, journaled on a 10 rod at the bottom of the casing, and having springs G, said levers moving freely at their upper ends in slots e of the casing, rods H, connected to said levers E, and carrying shoes I,

which work in slots i, straps passing under the spools and connecting the crank-levers with 15 the levers E, and devices for locking the levers E, said devices being provided with an alarm adapted to give notice of the unlocking of the said lever, as set forth.

In testimony that I claim the foregoing as 20 my own I have hereto affixed my signature in presence of two witnesses.

JAMES STEPHENS.
